Inventor.

Frank M. Merritt

UNITED STATES PATENT OFFICE.

FRANK M. MERRITT, OF PENN YAN, NEW YORK.

CORN-PLANTER.

SPECIFICATION forming part of Letters Patent No. 269,088, dated December 12, 1882.

Application filed July 27, 1882. (No model.)

To all whom it may concern:

Be it known that I, FRANK M. MERRITT, a citizen of the United States, residing at Penn Yan, in the county of Yates and State of New York, have invented a new and useful Improvement in Fertilizing Attachments to Hand Corn-Planters, of which the following is a specification.

My invention relates to improvements in fertilizing attachments in which the fertilizer-distributer operates in conjunction with the seed-dropping mechanism; and the object of my invention is to provide a combined hand seed-planter and fertilizer-distributer simpler in construction, more durable and perfect in operation than those heretofore made. I attain these objects by the mechanism illustrated in the accompanying drawings, in which—

20. Figure 1 is a part vertical section of the entire machine. Figs. 2, 3, 4, and 5 are detail parts of my improvement. Fig. 6 is a plan view of armed distributor and bottom of fertilizer-box. Fig. 7 is a front view of presser-foot seed-lever and fertilizer-lever. Fig. 8 is an enlarged vertical section in part of my fertilizer device.

Similar letters refer to similar parts throughout the several views.

30. A represents the main staff, provided at its upper end with a handle for operating the U-shaped levers C and D through the medium of the presser-foot B, hinged between the flanged wedge-shaped shovel-piece E, secured 35 to the lower end of staff A.

Fastened to the upper end of the lever D, Fig. 7, is a small rod, d', connecting with a common seed slide or dropper, f, in the bottom of the seed-box H. Upon the opposite side of 40 the main staff A is a similar box, a', in which phosphate or other fine fertilizer is placed.

In the center of the bottom, b', of the fertilizer-box a' is a round hole, through which the bolt g, Fig. 8, is passed after passing through 45 the armed distributor-wheel I within the box, which is provided in its center with a square hole fitting the square portion of the bolt next its head, and made to turn thereby.

Next to and beneath the bottom piece, b', 50 and on the bolt g, is slipped the ratchet-lever K, the arm or extended part being provided

with a slot to receive the end L of the wire m passing from the presser-foot B through the upper end of the lever C. Upon the same bolt, and next the lever K, is screwed the horizontal 55 ratchet-wheel P, and made rigid therewith in a higher or lower position by the check-nut O.

Between the ratchet-wheel P, and in the opening p' of the lever K, is placed a loose pawl, e', toothed upon its lower surface to fit and engage with the ratchet-teeth of the wheel P. This pawl e' is carried backward and forward by the lever K, yet allowed to rise and drop freely upon the ratchet-wheel P.

To the forward side of the seed-channel y, 65 next the staff A, and to and between the levers C and D, is fastened a spring, s, which serves to throw the mechanism back to its normal position after being moved inward by the presser-foot B.

70. Through the inward side of the bottom piece, b', Fig. 6, and directly over the seed-channel y, is cut a radial opening, O', through which the fertilizer drops when carried over by the distributor-wheel I. In the fertilizer-box, and directly over this opening O' in the bottom, b', 75 fastened to the forward side of staff A and extending down to upper side of the distributor-wheel I, is a tube, C', flanged at its top to receive seed of any kind when wished to be 80 dropped at intervals by hand. A slide or cut-off, R, to regulate the quantity of fertilizer in a hill, is made to slide horizontally through the bottom piece, b', across the opening O', as shown in Fig. 6.

85. The operation of my fertilizer in connection with the seed-planter is as follows: When the planter is in its normal position, as shown by Fig. 1, the slide f in the bottom of the seed-box H has already deposited its regulated amount 90 of seed in the seed-channel y. The shovel E is forced into the ground. The handle is then thrown forward until the seed-channel comes in contact with the levers C and D by the presser-foot resting upon the ground. In this 95 position the shovels are apart and the seed has dropped from the seed-channel into the ground, the lever C, through the medium of the wire L, slotted lever K, pawl e', ratchet-wheel P and bolt g, has caused the distributor-wheel I to make one-eighth of a revolution over the opening O', depositing fertilizer in the hill 100.

after the seed, the slide *f* has moved into the seed-box ready to bring forth more seed. The planter, if now lifted from the ground, allows the spring *S* to quickly shut the shovels, depositing more seed into the channel and slipping the pawl *e'*, which rises vertically in the opening *P'* of lever *K*, backward into the next notch of the ratchet-wheel *P*. The distributor-wheel *I*, moving in the fertilizer, causes sufficient friction to keep the mechanism from moving backward.

Having thus fully described my invention, what I claim, and wish to secure by Letters Patent, is—

1. In a planter, the combination, with the 15 radially-opened bottom piece, *b'*, the horizontally-armed distributor-wheel *I*, bolt *g*, ratchet-wheel *P*, pawl *e'*, slotted lever *K*, and slide *R*.

2. The combination, with the slotted lever *K*, of the wire *L*, the U-shaped levers *C* and *D*, and spring *S*, all substantially as and for the purpose set forth.

FRANK M. MERRITT.
